(57) **CLAIM**

The ornamental design for a display screen or a portion
thereof with graphical user interface, as shown and
described.

DESCRIPTION

The FIGURE is a front view of a display screen or a portion
thereof with graphical user interface.

The outer broken line represents a display screen or a portion
thereof and forms no part of the claimed design. The broken
line showing of the remainder of the graphical user interface
forms no part of the claimed design.
